Chavelang F. Dunderdale

UNITED STATES PATENT OFFICE.

CLEAVELAND F. DUNDERDALE, OF NEW YORK, N. Y.

IMPROVED MACHINE FOR GENERATING AND CARBURETING GAS.

Specification forming part of Letters Patent No. 92,943, dated July 27, 1869.

To all whom it may concern:

Be it known that I, CLEAVELAND F. DUNDERDALE, of the city, county, and State of New York, have invented a new and useful Improvement in Machines for Generating and Carbureting Gas; and I do hereby declare that the following is a full, clear, and exact description of the construction and operation of the same, reference being had to the annexed drawing, making part of this specification, and to the letters of reference marked thereon.

The figure represented in the drawing shows a vertical section of my improved apparatus.

The nature of this invention consists in certain improvements on a similar apparatus, for which Letters Patent were issued to me on the 1st day of June, 1869, and relates to certain means for checking the back flow of the gas contained in the gasometer, or some of its compartments, when any of the screw-caps are removed to supply the apparatus either with hydrocarbon liquid or with the pieces of zinc or iron turnings; also, in the arrangement of a flange or skirt around the perforated chamber containing the pieces of metal, to prevent the escape of the hydrogen; and, further, in the arrangement of a receptacle attached to the outlet-pipe for the gas, for the purpose of receiving any moisture that may be carried over with the gas, preventing thereby its collection in the pipes and choking the same.

The construction and operation of this apparatus being the same as described in the above-mentioned Letters Patent, I shall only describe those parts which are new and form part of my improvement.

Into the ends of the pipes F, which are there turned upward, I arrange self-acting valves *a*, through which the hydrogen gas from the chamber D can freely escape into the hydrocarbon liquid contained in the compartment E, but which will close immediately to prevent the hydrocarbon liquid from filling said pipes. *w* represents similar valves placed over the holes *m*, through the external walls of the chamber E, which permit the carbureted gas to escape into the cover or gasometer B, but prevent a back flow and escape of gas when the cap G is removed to supply the hydrocarbon liquid into the compartment E.

N is a flange or skirt encircling the perforated part of the compartment D, and is fastened to the same where it is attached to the compartment E, or where the latter finishes. This flange N is flared outward, and extends some little distance below the bottom of this perforated basket or compartment D, so that the diluted acid may flow in and out of said compartment through its perforations, and thus have free access to the metal scraps, and also wash out any sediment of the metal oxide, but, at the same time, prevent any escape of the hydrogen, particularly when this compartment is partly or wholly raised out of the acid, causing thereby the hydrogen to ascend and pass into the pipes F, provided for the purpose of conducting the same below the surface of the hydrocarbon liquid. Inside of this perforated part of the basket or chamber D a wire-cloth, *x*, is arranged to prevent the fine particles of its contents falling into the diluted acid-tank A.

M is a vessel or chamber attached to the outlet-pipe L, outside of the tank A, provided with a faucet. This vessel is for receiving any condensed moisture or vapor that may be carried over into the pipe L with the gas, preventing its collection in the pipes and choking the same. The faucet is for drawing off the same.

W is a man-hole for removing any deposit or sediment that may collect in the bottom of the tank A, by which the same can be removed without taking off the cover or allowing the gas to escape.

What I claim as my invention, and desire to secure by Letters Patent, is—

The combination of valves *a* and *w* with the hydrocarbon chamber and pipes, the flange or skirt N, surrounding the perforated compartment of the chamber D, and the wire-cloth *x* on the inside of said chamber, the screw-cap or man-hole W, and the condensing-receptacle M, arranged and combined and used in connection with a gas-generator, substantially as herein specified and described, and for the purpose set forth.

CLEAVELAND F. DUNDERDALE.
